UNITED STATES PATENT OFFICE.

VICTOR JAGGI, OF PHILADELPHIA, PENNSYLVANIA.

IMPROVEMENT IN LOOM PATTERN-CHAINS.

Specification forming part of Letters Patent No. 150,325, dated April 28, 1874; application filed October 6, 1873.

To all whom it may concern:

Be it known that I, VICTOR JAGGI, of the city and county of Philadelphia and the State of Pennsylvania, have invented a new and useful Improvement in Pattern-Chains of the Box-Motion of Looms; and I do hereby declare the following to be a clear and exact description of the nature thereof, sufficient to enable others skilled in the art to which my invention appertains to fully understand, make, and use the same, reference being had to the accompanying drawings making part of this specification, in which—

Figure 1 is a top or plan view of the device embodying my invention, a number of the links of the chain being opened. Fig. 2 is a central vertical section thereof. Fig. 3 is a view of the inside of detached parts.

Similar letters of reference indicate corresponding parts in the several figures.

It is well known that in the pattern-chain the removal of the links for change in the pattern is attended with considerable inconvenience, owing to the difficulty of forcing out the pintles which connect the links. There also exists a great liability of loss of the pintles, whereby the chain is detached and thus rendered inoperative, and the separated parts thereof endanger adjacent portions of the loom.

My invention is designed to remedy these defects; and consists in forming the links in sections or divisions, and uniting the sections by means of the pattern-pins, so that the links may be conveniently separated, and the pintles made correspondingly accessible. It also consists in constructing the pintle solid with one section, and fitting it in depressions in the two adjacent sections, whereby the pintle is greatly strengthened, and displacement thereof prevented. It also consists in shoulders on the sections, for preventing lateral motion thereof.

Referring to the drawings, A represents the links, which are constructed in sections B B', formed by divisions of the links in their longitudinal and horizontal directions. C represents a pintle for connecting two adjacent sections, and is cast or formed solid with one section, B'. A depression, D, is formed in the ear's or portion of the section B opposite to the pintle C, and a similar depression, D, is formed

in a corresponding portion of the other section, B', so that when the two sections are together, the two depressions form a complete cavity in one link for the reception of the pintle of the adjacent link. In order to hold the two sections, and thus connect the links, screws E are passed through the said sections, and their heads are of varying dimensions for the purposes of the pattern, as is well known. The inner face of the central portion F of the pintle, or the part of the section B' that joins the pintle, is shouldered, and the inner face of the portion G of the section B which corresponds to the portion F is likewise shouldered, said portion G in one section being arranged between the ears of the next section, and, the shoulders of the two sections engaging and being thus locked, the lateral play of the sections is prevented, and thus the axial motion of the links is in nowise interfered with.

When the sections are attached to each other the links are firmly connected, and the pintles completely embedded or inclosed, so as not to be exposed, whereby liability to displacement is overcome, and separation of the links prevented.

When the pattern is to be changed, the pintles are not to be driven from the links to separate the chain; but the sections are merely opened, the arrangement relative to the pattern is effected, the sections are applied to each other and the screws properly fitted thereto, whereby the chain is again in practical condition.

Having thus described my invention, what I claim as new, and desire to secure by Letters Patent, is—

1. The pattern-chain link, formed in sections B B', united by means of the pattern-pin, substantially as and for the purpose set forth.

2. The sections B B', provided with the solid pintle C and depressions D, all constructed and operating substantially as and for the purpose set forth.

3. The sections B B', provided with the shoulders F G, substantially as and for the purpose set forth.

VICTOR JAGGI.
